UNITED STATES PATENT OFFICE.

MATTHEW MARSHALL, SR., OF PORT COQUITLAM, BRITISH COLUMBIA, CANADA.

COKE-PRODUCING AND BY-PRODUCT-RECOVERY METHOD.

1,248,883.

Specification of Letters Patent. Patented Dec. 4, 1917.

Application filed August 14, 1917. Serial No. 186,211.

To all whom it may concern:

Be it known that I, MATTHEW MARSHALL, Sr., a subject of the King of Great Britain, and a resident of Port Coquitlam, in the Province of British Columbia, Canada, have invented certain new and useful Improvements in Coke-Producing and By-Product-Recovery Methods, of which the following is a specification.

10 My invention relates to improvements in methods for producing coke and recovering by-products from the coal at the same time, and the object of my invention is to devise a method whereby all the available by-products from the volatile constituents of the coal may be recovered without reducing the quantity or impairing the quality of the coke produced.

15 In my United States Patent No. 1,227,060, dated May 22, 1917, I have shown and described fully a coking oven suitable for the carrying out of my method, but for the better understanding of this present specification I annex a figure showing a cross sectional elevation of the oven, to which reference is made and in which 2 represents the fire-brick lined dome structure of the walls and roof, 3 a closable aperture in the crown, through which the oven is charged with coal, 20 and 4 the uptake flue aperture. The side door opening through which the coke charge is withdrawn is not shown.

25 5 indicates the sub-floor sloping conically to the central well aperture 6, which aperture is covered by a grating 7 and from which a pipe 8 closable by a stop-cock leads to the condensers in which the by-products are recovered. 9 indicates the gravel or rock with which the conical space within the sub-floor is filled, on the upper surface of which 30 fire-brick tiles 10, are laid in parallel rows with an interspace 11 between each row of tiles, while along the side edges of these tiles and also along the middle of each row are 35 placed firebricks 12 and 13 respectively, the firebricks 12 being checked on their upper sides to form channels, the middle rows of bricks 13 being without checks. Resting on the upper sides of the firebricks 12 are firebricks 14 and resting on each middle row of 40 bricks 13 is a row of bricks 15, the middle of each side of which for a depth of about 45 two inches is checked so as to form interspaces 16 between them and the bricks 14

and therebeneath these bricks are beveled inward to where they seat upon the bricks 13, from which it will be seen that the bricks 14 and 15 form the floor of the oven, which floor is provided with interspaces 16 through which the volatile matter from the coal being coked may pass freely into the channels between the bricks 12 and 13 and therefrom through the channels formed by the checks of the bricks 12 and through the gravel 9 and thence through the well 6 into pipe 8 55 to be drawn therethrough for delivery to the condensers.

17 indicates an injector through which steam or air may be introduced into the interior of the oven.

70 In use, the oven is charged through the central aperture 3 to a depth of about three feet, the side door being closed. The charge being kindled the draft is first taken through the uptake flue 4 and the fire is allowed to spread over the whole upper surface of the charge until it attains a red glow. Thereafter the uptake flue is closed and a down draft is induced by means of a rotary pump or otherwise through the pipe 8, this down draft being assisted by a stream of steam and air at the injector 17.

75 The heat from the upper strata of the charge is thus drawn downward through it and the volatile matter from the coal, released by the heat, passes downwardly through the firebrick floor and tiles of the oven in separate streams and then through the gravel to the pipe 8 whereby all the 80 available by-products of the coal are recovered while at the same time the maximum 85 quantity of coke is obtained and of an improved quality.

90 What I claim as my invention is:—

95 The method of producing coke and recovering the by-products thereof consisting in inducing a downward draft through a heated charge of coal whereby the heat from the upper strata of the charge is drawn downward through it and the volatile constituents 100 are given off, then passing such constituents downwardly in separate streams and then through a finely divided material to the condensers.

105 Dated at Port Coquitlam, B. C., this 7th day of August, 1917.

MATTHEW MARSHALL, SR.
